CLOSURE FOR STEAM STERILIZERS

Maurice Bramson, Brooklyn, N. Y.

Application September 28, 1943, Serial No. 504,101

10 Claims.

(Cl. 220—36)

The present invention relates to closures for steam sterilizers, more particularly to those of the type used in connection with hospital operating rooms.

Sterilizers of the type to which the present invention relates generally have a large circular opening in a ring set into the end wall of a cylindrical drum and having an inwardly facing seat, and the door is in the form of a disk disposed inside the sterilizer and provided with a conical mating face, so that when the door is open access may be had to the interior of the sterilizer, and, when the door is closed and steam pressure applied, pressure against the inner face of the door holds the seats in close contact.

The present invention contemplates the employment of an arm on a vertical shaft pivoted in the top of the sterilizer drum and connected to the door to swing it back and forth over an arcuate track. The arm has a lost motion connection with the door so that it may swing freely, and the arm is resilient so as to exert mechanical pressure on the door when opposite the seat, whereby the door is held closed sufficiently tight to avoid the escape of steam vapors while the pressure is being built up. The track is also preferably sloping and the door has a stud extending through a vertically elongated slot in the arm.

Other and further objects will hereinafter appear as the description proceeds.

The accompanying drawing shows, for purposes of illustrating the present invention, an embodiment in which the invention may take form, it being understood that the drawing is illustrative of the invention rather than limiting the same.

In the drawing:

Figure 1 is a perspective view of the sterilizer with the door partly open;

Figure 2 is a horizontal sectional view on the line 2—2 of Figure 1 showing the door closed in full lines and showing the door fully open in dotted lines;

Figures 3 and 4 are vertical sectional views on the line 3—3 of Figure 2, the door being open in Figure 3 and closed in Figure 4; and

Figure 5 is a fragmentary sectional view on the line 5—5 of Figure 3.

The sterilizer 10 has the usual horizontal cylindrical drum with inner and outer walls 11 and 12 respectively, a closed rear end (not shown) and a front end wall 13 carrying a ring 14 provided with an inwardly facing conical seat 15. The door 16 which closes the opening in the ring 14 has a conical seat 17 on its outer surface

adapted to mate with the conical seat on the ring as usual.

The novel arrangement herein for operating the door to open and closed positions includes a shaft 20 extending through the top of the drum at a suitable distance from the front end of the sterilizer, provided with an external handle 21 and an enclosed, preferably arc shaped, arm 22 which extends down to the center of the door.

The door 16 has a rearwardly extending threaded stud 23 which passes through a vertically elongated aperture 24 in the lower free end of the arm 22. A bearing washer 25 is placed on the stud ahead of the arm and accidental separation of the parts is prevented by a cap nut 26 threaded on to the stud. This cap nut may, if desired, be secured to the stud by a pin 27.

The ring 14 has a rearwardly extending lug 30 at the bottom, and to this lug is secured the front end 31 of an arcuate track 32. The rear end 33 of this track is secured to the inner wall of the drum. The inner end of the track is preferably at a higher elevation than the front end. This track is of channel shaped cross section as will be apparent from Figure 5. The track receives the peripheral edge or rim 34 of the door.

The weight of the door is at all times taken by the track 32. When the door is in the full open position, as indicated in Figures 3 and 5, and in the dotted line position of Figure 2, the stud 23 is near the top of the slot 24, and, while the door cannot separate from the stud, it is held somewhat loosely, that is to say it can be twisted somewhat about a vertical axis through the center 35 of the door when in this position and can be tilted back and forth to some extent. While it is supported by the track it floats somewhat freely on the arm. Ordinarily there is a substantial space between the washer 25 and the adjacent end of the arm. This space is indicated at 36 in Figure 5.

When the door is in the full open position the edge or rim of the door is, as shown in dotted lines in Figure 2, close to the conical face of the fixed ring 14. When the door is to be shifted from full open position to closed position the arm 22 moves to bring the right hand side of the slot (Figure 3) against the stud and then the door rolls along the track, and as the track slopes the door lowers and the closing is rendered easy. The edge of the door travels along the path indicated by the dot-and-dash line 36 of Figure 2.

When the edge of the door has reached about the point marked X in Figure 2 the seating

surface 17 of the door comes into engagement with the seating surface of the ring at one point and from there on in the closing movement the path of the door is determined by the wiping action of these two surfaces, and the parts are so proportioned that the periphery of the door passes in by the seat as the door is brought to full closed position. During this movement the door has been compelled to move toward the axis of the shaft 20 and now instead of having a space 35 between the door and the arm 22 the door has pressed back against the arm, and, as the arm is yieldable, has flexed the arm slightly so that considerable mechanical pressure exists between the door and the fixed ring. There is now a gap at 37 between the arm 22 and the nut 26 and the stud 23 is in the lower part of the slot. In order to prevent moving the door past closed position a stop 38 is carried by the ring 14.

It will thus be seen that the present invention provides a closure arrangement for sterilizers of this character in which the opening and closing movement of the door is effected by a suitably located external handle. The door is always held securely in position and is not likely to loosen or shift from this position, and it can be readily fastened in the closed position for shipment. The arm 22 occupies no otherwise useful space in the sterilizer, as it is out of the way when the door is open so that there is nothing to interfere with inserting and removing objects, and when in the closed position it is well in front of any objects which may have been put into the sterilizer.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. In a steam sterilizer having a steam tight body and an end wall carrying a ring disposed below the top of the body and laterally of the side of the body, the ring being in a vertical plane to define an opening and having an inwardly facing conical seat, a closure having a mating conical face and a rim adjacent the conical face of larger diameter than the conical face, and a fixed track extending laterally of the opening along which the rim of the closure may roll when the closure is moved to and from the closed position, the improvement according to which the closure has an inwardly extending central stud, the top of the body carries a vertically rotatable, inwardly protruding shaft mounted to the rear of the center of the ring and carrying an externally accessible operator for turning the shaft, and on its lower end an arm extending from the shaft toward the closure and having its lower end provided with a slot which receives the stud so that the turning of the shaft back and forth will swing the arm back and forth and bring one or the other of the slot walls against the stud and move the closure back and forth with its weight supported by its periphery rolling along the track.

2. The improvement claimed in claim 1, wherein the arm is resilient and exerts pressure on the inner face of the closure when brought to the closed position to hold the closure face against the seat.

3. The improvement claimed in claim 1, wherein the stud has a nut which is spaced from the inner face of the arm when the closure is seated whereby the stud may shift back and forth in the aperture when the closure is unseated and the closure may then be relatively loose.

4. The improvement claimed in claim 1, wherein the track slopes upwardly from the bottom of the ring and the slot is vertically elongated so that the stud may raise and lower relative to the arm.

5. The improvement claimed in claim 1, wherein the stud fits loosely in the slot to allow limited vertical movement of the closure relative to the arm, limited horizontal movement of the closure relative to the arm and limited tilting movement of the closure relative to the arm when the closure is free of the seat, and the arm is resilient and exerts pressure on the inner face of the closure when brought to the closed position to hold the closure face against the seat.

6. A steam sterilizer having a horizontal cylindrical body with a fixed end wall having a large opening in a vertical plane about which is an internal seat, and an arcuate track extending from below the center of the opening about the end wall and secured to the inside of the body, the track sloping upwardly toward said body, an arm disposed inside the sterilizer body and pivoted thereto to swing about a vertical axis in the vertical axial plane of the body, the lower end of the arm having a vertical slot and the arm being shaped to have its lower end swing from a position slightly to the rear of the opening toward the side of the sterilizer body, and an annular closure having a rearwardly extending stud extending through the slot in the arm and carrying an abutment which presses the closure against the seat.

7. In a sterilizer of the like, a sterilizer body having a circular opening in a vertical plane, a circular closure for the opening, the closure being disposed inside the body larger than the opening and having an inwardly extending axial stud, a fixed arcuate track with which the closure edge is in rolling engagement in moving between open and closed position and sloping so that the closure is at a lower elevation when closed than when open, an arm pivotally supported in the body to swing about a vertical axis to the rear of the center of the opening and substantially coincident with the center of curvature of the arcuate track, and means interconnecting the free end of the arm and the stud for exerting force on the closure for moving it back and forth, said means including a self-accommodating driving connection which compensates for the differences in elevation of the stud and arm support.

8. In a sterilizer or the like, a sterilizer body having a circular opening in a vertical plane, a circular closure for the opening, the closure being disposed inside the body larger than the opening and having an inwardly extending axial stud, a fixed arcuate track supporting the closure in open and closed position and sloping so that the closure is at a lower elevation when closed than when open, and an arm pivoted to swing about a vertical axis to the rear of the center of the opening and having a vertical slot through which the stud extends whereby the closure may move downwardly as it is swung toward closed position, the axis about which the arm swings and the maximum radius of the arm being such that the arm bears against the closure when in the closed position to press it against the seat, the arm and

closure having horizontal lost motion so that the unseated closure is carried loosely.

9. The improvement in sterilizers or the like wherein the body of the sterilizer has a circular opening of smaller diameter than its horizontal width, the opening being in a vertical plane and having an inwardly facing seat, comprising a disk shaped closure for the opening disposed within the body, a closure supporting track inside the sterilizer body and extending laterally from the bottom of the opening in a path arcuate about a vertical axis disposed inwardly of the center of the opening and sloping upwardly so that the closure is at a higher elevation when shifted away from the opening along said track, an arm pivoted about said axis, and means interconnecting the free end of the arm and the closure for exerting force on the closure for moving it back and forth along the track, said means including a self-accommodating driving connection which compensates for the differences in elevation of the closure and arm support.

10. In combination, a fixed vertical ring having

on its inner face an outwardly flaring conical seat, an annular closure disk having a mating conical face and a rim larger in diameter than the conical face, a fixed substantially horizontal arcuate track of upwardly opening channel shaped cross section extending away from the bottom of the ring and along which the rim rolls as the closure moves toward and away from the seat, the curvature of the track being such that as the rim rolls along it the rim remains close to the seat on the ring, an arm pivoted about a fixed vertical axis at approximately the center of curvature of the track and having an aperture at its lower end through which an axially disposed stud on the disk extends there being lost motion axially of the stud when the disk is unseated, the arm being resilient and its normal radius where it bears against the disk being more than the distance from the shaft axis to the same point when the disk is seated whereby the arm is bent to yieldingly hold the disk in seated position.
